UNITED STATES PATENT OFFICE.

ALBERT N. EATON, OF OMAHA, NEBRASKA.

BARREL-HOOP MACHINE.

1,390,282.

Specification of Letters Patent. Patented Sept. 13, 1921.

Application filed August 17, 1920. Serial No. 404,093.

To all whom it may concern:

Be it known that I, ALBERT N. EATON, a citizen of the United States, residing at Omaha, in the county of Douglas and State 5 of Nebraska, have invented certain new and useful Improvements in Barrel-Hoop Machines, of which the following is a specification.

The present invention relates to improvements in barrel hoop forming machines, and has for an object to provide an improved machine of this character which will be capable of forming a barrel hoop in a single operation without the use of 15 rolling mills or presses in the manner at the present time done.

Another object of the invention resides in providing an improved barrel hoop forming machine which will be rapid in operation, serving to produce great numbers of 20 the hoops in a minimum space of time and at a saving in labor and operating costs.

A further object of the invention is to provide a compact and simple machine for 25 carrying out the above described purposes which may be installed in conjunction with the usual punch press.

With these and other objects in view the invention consists in the novel details of 30 construction and combinations of parts more fully hereinafter disclosed and particularly pointed out in the claims.

In the accompanying drawings forming a part of this application, and in which similar reference symbols indicate corresponding parts in the several views:

Figure 1 is a side elevation of an improved device constructed in accordance with the present invention, and illustrated 40 as resting on the bed of a punch press, which is shown partially in section and with the punch elevated above the same and partly broken away.

Fig. 2 is a plan view of the same with the 45 punch removed.

Fig. 3 is a longitudinal sectional view taken on the line 3—3 in Fig. 2.

Fig. 4 is a plan view of the die guide plate.

50 Fig. 5 is a similar view of the die top plate.

Fig. 6 is a sectional view taken through a hoop formed by the improved machine.

55 Fig. 7 is a similar view of a metal ring prior to its insertion in the machine.

Fig. 8 is a plan view, on an enlarged scale, of one of the die segments; and

Fig. 9 is a side view of one of the connecting links.

Referring more particularly to the drawings, 10 designates the bed of a punch press, 11 the punch, and 12 the punch point. These parts are old and well known and constitute no portion of the present invention.

The invention more particularly consists in the provision of a device mounted upon the bed 10 and adapted to receive a ring 13, such as shown in Fig. 7, and provided with die segments of an expansible character that are moved by suitable devices mounted in conjunction with the punch point 12, whereby a bead 14 of the character shown in Fig. 6 may be provided on the finished hoop.

This bead 14 is pressed outwardly from the central part of the hoop 13, and it imparts stiffness to the hoop, is ornamental, and has other well known desirable features. It is the object of this invention to provide 80 a device for forming this bead 14.

This device consists of a plate 15 having a central opening to receive a stud or post 16 which projects upwardly beyond the plate 15 and preferably seats within a socket 85 17 made in the bed 10; screws or other fastenings 18 may be employed to pass through the plate 15 about the post 16 and to enter the bed 10 in order to effectually hold the plate in place. The upper face 90 of the plate 15 is more particularly illustrated in Fig. 4, and possesses radially disposed slots 19 forming guide ways to receive centrally formed ribs 20 projecting beneath die segments 21, of which there are 95 any suitable number.

The die segments are arranged edge to edge and form a complete circle surrounding the post 16. The outer arcuate edges of the die segments are formed with punch 100 beads 22 adapted to enter punch sockets 23 in an outer ring 24 which rests upon the bed 10 and embraces the segments. A slot 25 is left between the ring 24 and the beads 22 when they are in a retracted position, to 105 permit of the insertion of the stave ring 13 in the manner shown in Fig. 3. The ring 13 is supported on its edge by the bed 10 and the arrangement of parts is such that when driven outwardly the beads of the segments 110

will force the intermediate portion of the metal constituting the ring 13 into the socket 23 so that the bead 14 will be produced in a single operation.

5 The segments 21 at their inner edges are provided with pins 26 adapted to be engaged by the outer ends of links 27, which extend diagonally and are coupled between ears 28 on an anvil member 29 which rests 10 beneath the punch point 12, as shown in Fig. 1.

A top plate 30, shown more particularly in Fig. 5, rests upon the segments 21 and is of considerable weight in order to impose 15 a pressure thereon to hold them in their correct relative positions. The plate 30 is slotted radially, as indicated at 31, along suitable lines to agree with the positions of the various links 27, in order that these 20 links may have freedom of operation.

The various links, as shown in Fig. 9, are provided with perforations 32 and 33 at their opposite ends that they may receive the coupling pins by which they are respectively secured to the segments 21 and the 25 anvil member 29. The anvil member 29 is provided with a depending bearing 34 slidably fitted over the upper end of the post 16, a coil spring 35 being employed to hold 30 the anvil member 29 in the elevated position shown in Figs. 1 and 3. This coil spring is arranged between the central portion of the base plate 15 and the under side of the anvil member.

35 As shown more particularly in Fig. 2, the ring 24 is composed of a pair of sections hinged together for instance at 36, and provided at their opposite sides with lugs 37 adapted to receive a U-shaped 40 clip 38 constituting substantially a clamp and having a set device 39 by which the lugs 37 may be forced tightly together.

As these barrel hoops are formed at the present time they are subjected to what is 45 known as the "rolling process," which is expensive and slow. This process consists in cutting a strip of metal to a suitable length, forming it into a ring, and welding its ends together. This is an initial step 50 by which the ring 13 in Fig. 7 is produced. This method is still carried on in accordance with the present invention. However, the old process consisted in placing the ring 13, formed as just mentioned, between rollers 55 which would by a gradual process form the crimp or bead therein. Gradual pressure according to the old process was put upon the ring, so that the bead or crimp was formed slowly; this process being carried 60 out until after subjection to a required pressure, the desired amount of crimp was formed.

65 By use of the present invention the band such as formed in ring 13, is placed in the position shown in Fig. 3 and the punch point

12 is allowed to descend upon the anvil 29. As it does so it will depress the anvil in opposition to the action of the coil spring 35, which will be correspondingly compressed, and through the action of the links 27 die 70 segments 21 will be forced outwardly, they being guided by the ribs 20 and slots 19. The bead 22 will therefore press the metal of the ring 13 into the sockets 23 in the outer member 24, and the crimp in the barrel hoop will be formed quickly and in one operation. 75

After the punch point retires upwardly the coil spring 35 will restore the parts to the position shown in Fig. 3, withdrawing the die segments and permitting of the withdrawal of the hoop just formed, which may be done by separating the two half sections of the ring 24.

It is obvious that those skilled in the art 85 may vary the details of construction and arrangements of parts without departing from the spirit of my invention, and therefore I do not wish to be limited to such features except as may be required by the claims.

I claim:

1. A barrel hoop forming device comprising a pair of relatively movable die members having means to form a crimp in a hoop, an anvil connected to one of said die members and adapted to drive the same into operative relation with the other die member to form the bead in said hoop, yieldable means acting on said anvil member to hold the same and the connected die member in a normally inoperative position, a base plate 100 beneath the movable die members having means to guide their movements, and means projecting up from the plate and slidably engaged with the anvil to direct its motion. 90

2. In combination with a punching machine having a bed and a punch point, of an anvil located beneath the punch point and adapted to be operated thereby, reciprocating punch segments, links connecting said segments and anvil, spring means for yieldingly holding the anvil elevated, means to guide the anvil in its reciprocating movement, a base plate adapted to rest on the bed of the punching machine and having guideways to direct the movements of the segments, a weight plate placed upon the upper portions of said segments, and a die ring surrounding said segments and spaced therefrom, substantially as described. 110

3. A machine as described comprising an outer die ring, a base plate lying within the ring, radially-reciprocating die blocks on the plate to coöperate with the ring, complementary means between the plate and blocks to guide the movements of the latter, an anvil initially held in an upper position, connections between the anvil and die blocks, a weight plate resting on the die blocks, and means to guide the movement of the anvil. 120

4. A machine of the character described 130

comprising a base plate adapted to be affixed to a support and having a number of radial grooves made in its upper face, a series of die segments having ribs on their lower sides 5 slidably fitted in said grooves, an anvil lying above the central portion of the base plate, means extending up from the plate for guiding the movement of said anvil, spring means extending beneath the base 10 plate and anvil for holding the latter in an

upper initial position, an outer die ring in spaced relation about said plate and segments, and a weight plate lying upon said segments.

In testimony whereof, I have affixed my 15 signature in presence of two witnesses.

ALBERT N. EATON.
